UNITED STATES PATENT OFFICE.

FRANK A. NIEBERDING, OF CLEVELAND, OHIO.

STOVE.

1,370,704.

Specification of Letters Patent.

Patented Mar. 8, 1921.

Application filed March 26, 1917. Serial No. 157,345.

To all whom it may concern:

Be it known that I, FRANK A. NIEBERDING, a citizen of the United States, residing at Cleveland, in the county of Cuyahoga and 5 State of Ohio, have invented a certain new and useful Improvement in Stoves, of which the following is a full, clear, and exact description, reference being had to the accompanying drawings.

10 This invention relates to improvements in gas heating stoves, especially to the sort wherein "artificial fuel" is employed, and more particularly to the open front type.

The invention has for its main object the 15 production of a stove of the above character wherein the maximum of efficiency is obtained from the products of combustion and yet wherein such products are thoroughly disposed of through the flue, expelling into 20 the room only pure, warm air.

My invention contemplates the use of long slender radiants, and which, as is well known to those familiar with this class of heaters, are very fragile. A further and 25 important object of the invention is to provide a novel construction wherein these radiants are permitted to repose in an inclined position without the need of additional holding means, allowing the use of 30 fractured or even broken radiants, when the break or injury is not too serious. Following from this arrangement is a further object of providing a construction which encourages and, under normal conditions, 35 compels the products of combustion to follow the inclination of the radiants to the exhaust flue above, and further provides for the inclusion of means for recovering any products which might be diverted from the normal course, through 40 some external cause, and leading them finally to the exhaust flue.

A further and more general object of the invention is to combine the advantages of 45 heat reflection and heat radiation in one structure to the attainment of the highest efficiency, and then again, more limitedly, to provide a construction which is comparatively simple and inexpensive of manufacture and through which this and the preceding 50 objects are attained. Such a construction is illustrated in the accompanying drawings wherein Figure 1 is a front elevation of a gas heating stove constructed in 55 accordance with my invention, portions of the front being broken away to reveal cer-

tain details; Fig. 2 is a front-to-rear central vertical section through the stove; Fig. 3 is a horizontal section on the line 3—3 of Fig. 2, looking downward; and Fig. 4 is a section 60 on the line 4—4 of Fig. 2, looking in the direction of the arrows.

The casing of the stove is preferably formed of sheet metal and is shown as comprising a top 1, side walls 2, back wall 3, 65 and bottom plate 4. The front edges of the top and side walls are connected to a flange 5 which extends rearward from a front frame 6, the frame herein being shown as extending across the upper portion of the 70 front of the casing where it is provided with openings 7, and down each side of the casing to and across the bottom, the bottom portion having an opening 8 for the admission of fresh air to the casing. The 75 front frame 6 may be formed of sheet or cast metal, and between its upper and lower portions, having respectively the openings 7 and 8, is located the main opening. A hood 10 projects through the upper portion of the 80 main opening of the frame and may be held in place by having its flange 11, which extends across the top and down the sides of the hood, attached to the adjacent portion of the frame.

Inclined upward from the bottom of the front frame, just above its opening 8, is a plate 15 which, as will be seen clearly from Figs. 1 and 3, is corrugated to produce vertical troughs 16, the ends of the plate being 90 flanged downward for connection with the side walls 2. That portion of the casing to the front of the plate 15, may be considered the combustion space, and it is closed at its upper end, except for a flue passage that 95 will be presently pointed out, by a plate 18 which is flanged upward at its ends for connection with the end walls 2, and has its rear end turned downward behind for connection with the upper edge of the plate 15, 100 while its forward end is shown as contacting with the front frame at the top of the hood 10.

A heat reflector 20, in the form of a plate, has its ends flanged upward and connected 105 to the end walls, similarly to the previously described plates, and is spaced a sufficient distance below the plate 18 to provide between the two plates an ample passage-way for the products of combustion from the 110 combustion space below. As to the shape of the plate, it will be observed that its for-

ward portion is substantially horizontal and located well above the lower edge of the hood 10 while the remainder of the plate is inclined downwardly from such portion toward the plate 15 where its extreme rear edge is turned downward and then backward and upward quite near the upper end of the plate 15. Each end of the horizontal portion of the plate 20, is provided with 10 openings 21, as shown particularly in Fig. 1.

The plate 18 has an opening through which a collar 24 is shown as projecting, to provide an outlet for the combustion space; and an outlet pipe 25 projects through an 15 opening in the upper end of the back wall 3 for connection with a flue. A radiator 26, which consists of a series of hollow rectangular casings, is interposed between the outlet pipe 25 and the collar 24 and the combustion space has communication with the flue through this radiator, the collar 24, and the aforesaid pipe 25. The two central casings of the radiator are communicatively connected at about their longitudinal center 20 through a pipe section 27, and the central portion of each end casing has a tubular extension, one for connection with the collar 24, and the other with the outlet pipe 25. Each end of each of the end casings of the 25 radiator has communication with the adjacent end of the adjoining casing through a pipe section 29. Thus it will be seen that a tortuous course is provided for the products of combustion from the combustion space to 30 the flue, and during their travel the products are compelled to contact with considerable radiating surface, so that practically their full heating value is abstracted before they reach the flue, and in the event that their 35 free passage through the radiator should be too rapid to assure such efficiency, their velocity may be retarded by a damper 30 which is supported within the pipe 25 upon and fixed to a shaft 31, the upper end whereof is formed into a crank 32 for connection 40 with and operation by a rod 33, the forward end of which projects through an opening in the front frame 6 and is there equipped with a knob 34. Excessive movement of the rod 45 in a forward direction is prevented by a stop 35, shown as consisting of a cotter pin extending through an aperture in the rod the movement being so limited as to prevent the crank from assuming a "dead center" 50 position. The damper is shown as provided with a central opening for the purpose of safety, to avoid a complete closure of the 55 outlet.

A battery of burners 40, preferably of the 60 Bunsen type, are communicatively connected to a manifold 41, which is supported, at its ends, in brackets 42, from the adjacent bottom portion of the front frame 6. It will be seen from Fig. 1 that a burner 40 is provided for each of the troughs 16 of the plate

15 and reclining within each trough above the burner is a radiant 45, the same being shown as supported at its lower end by a lug 46 which projects from the bottom of the trough in proximity to the end of the 70 burner. The radrients 45 are hollow and their walls are of skeleton formation to permit of a thorough circulation of the products of combustion about every portion of the respective elements. 75

A suitable fender 50 is arranged to stand in front of the lower end of the casing and conceal the burners and manifold, the rear edge of the top of the fender reposing in juxtaposition to the lower ends of the radrients. The front of the fender has air admitting openings 51, and at about its center, is provided with a key receiving socket 52 for the reception of the shank of the key 53 which is adapted to be applied to the outer 85 end of a rod 54 that extends through the wall of the fender into the key socket 52, the inner end of the rod having connection with a suitable valve 55 that may constitute a part of the burner structure. 90

An ornamental post 58 rises from the rear of each side of the fender and embraces the corner of the frame, 6 and near its upper end has connected to it the end of a guard rail 59 which extends across the front of the 95 heater in a position to answer as a foot rest, if desired.

When the burners are lighted, the products of combustion travel upward through and about the radrients and are discharged into the 100 space above the plate 20 from which they escape through the radiator 26 into the flue, via the course previously described in detail. Flue conditions being proper, the draft of the flue even with the safety damper 30 105 closed is sufficient to draw the products upward to the rear of the plate 20, and it is only under abnormal conditions, as when a draft is created in front of the heater from some external cause, resulting in an 110 eddy of air being produced within the combustion space, that any of the products of combustion are drawn forward of the plate 20. However, when the products are so diverted, they pass upward in front of said 115 plate and are trapped beneath the hood 10 from where they escape, through the openings 21, into the space between the plates 18 and 20, from where they pass out through the radiator and flue. A great percentage 120 of the heat generated is of course thrown off through the open front of the stove directly from the incandescent radrients, and the plate 20 serves to reflect considerable 125 of this heat downward and forward from the combustion space. It is obvious that the plate 15 becomes very hot from its contact with the radrients, and this plate radiates into the interior of the casing a very considerable amount of heat, as does also the 130

plate 18 and the casings of the radiator 26. Therefore, cool, fresh air which is drawn inward through the openings 51 of the fender and on through the opening 8 of the 5 front plate into the casing is heated to a very high degree as it passes upward in direct contact with the aforesaid plates and radiator prior to being expelled through the openings 7 of the front frame.

10 Thus it will be seen that advantage is taken of practically every means of obtaining the maximum amount of heat from the products of combustion before they finally reach the flue. And it will be recalled, while 15 considering this high efficiency, that no products of combustion are permitted to escape into the room.

It is clear from the foregoing construction that the radiants are supported solely by the 20 plate 15, making unnecessary any other means of suspension. Because of their inclination, fractured or broken or sectional radiants may be utilized, so long as the lower sections are capable of supporting the ones 25 thereabove.

Having thus described my invention, what I claim is:

1. In a heater of the class set forth, the combination with a casing, of a plate inclined upward and backward from the lower portion of the casing front, a second plate extending from the upper edge of the former plate forward to the front of the casing, a hood projecting forward and downward 30 from the front of the casing and terminating below the forward edge of the second plate, a partition spaced upward from the lower edge of said hood and extending therefrom backward and downward into proximity to the upper end of the first plate, thereby to provide beneath the hood a recovery space for products that would otherwise escape, the space between said partition and the second plate having an outlet and having 35 communication with the recovery space, and a combustion device arranged to project its products upward along the front of the first plate.

2. In a heater of the class set forth, the combination with a casing, of a plate inclined upward and backward from the lower portion of the casing front, a second plate

extending from the upper edge of the former plate forward to the front of the casing, a hood projecting forward and downward 55 from the front of the casing and terminating below the forward edge of the second plate, a partition spaced upward from the lower edge of said hood and extending therefrom backward and downward into proximity to the upper end of the first plate, said partition having openings in the vicinity of said hood, the space between said partition and the second plate having an outlet, and a combustion device arranged to project its products upward along the front of the first 60 plate.

3. In a heater of the class set forth, the combination of a casing, a plate inclined upwardly and rearwardly from the lower 70 front portion of the casing, said plate having radiant receiving depressions, an elongated tubular radiant resting within each depression and properly positioned thereby with respect to the other radiants and whereby 75 it is held against lateral displacement, and a combustion device arranged in operative relation to the radiants.

4. In a heater of the class set forth, the combination of a casing, a plate inclined upwardly and rearwardly from the front portion of the casing and corrugated to produce troughs extending from top to bottom of the plate, a lug projecting into each trough from the lower portion of the plate, an elongated 80 radiant reposing within each trough and supported by said lug, the troughs serving to properly position the radiants with respect to each other and whereby they are held against lateral displacement, and a combustion 85 device arranged in operative relation to the radiants.

5. In a heater of the class set forth, the combination of an open front casing, elongated radiants supported within the casing 95 and extending upwardly and rearwardly from the lower front portion thereof, a combustion device supported beyond the front of and entirely outside the casing in operative relation to the radiants, and a removable 100 fender concealing said device.

In testimony whereof I hereunto affix my signature.

FRANK A. NIEBERDING.
